(57) **CLAIM**

The ornamental design for the track-shoe, as shown and described.

DESCRIPTION

FIG. 1 is a perspective view of the track-shoe showing my new design;

FIG. 2 is a top plan view of the track-shoe;

FIG. 3 is a bottom plan view of the track-shoe;

FIG. 4 is a front elevational view of the track-shoe;

FIG. 5 is a rear elevational view of the track-shoe;

FIG. 6 is a right elevational view of the track-shoe; and,

FIG. 7 is a left elevational view of the track-shoe.

The broken line showing of a hole, aperture, or other ornamentation is included for the purpose of illustrating portions of the track-shoe and forms no part of the claimed design.
